LIFTING TRUCK

George Quayle, Philadelphia, Pa., assignor to
The Yale & Towne Manufacturing Company,
Stamford, Conn., a corporation of Connecticut

Application February 8, 1941, Serial No. 378,003

20 Claims. (Cl. 254—10)

This invention relates to an industrial lift truck of the type having a main frame or lifting head, an elevating frame mounted for lifting movement relatively to said main frame or lifting head, and lifting means for lifting said main frame relatively to said lifting head. My invention will, in this application be described as embodied in a truck of the type disclosed in the Stuebing Patent No. 1,785,368, which is owned by The Yale & Towne Manufacturing Company, the owner of 10 this invention.

It is one feature of my invention that the elevating frame of the truck is elevated, and then held elevated, through the intermediary of a spring which is preferably functionally interposed between the lifting means and the elevating frame. Through this relationship of the parts, it is obvious that the lifting action will be transmitted through a yielding medium, which is desirable in lifting many types of loads, and that similarly, the load will be held elevated by the same yielding medium.

As a further feature of my invention, the elevating frame is elevated by a lifting element which is part of the lifting means preferably carried on the main frame or lifting head. In the particular truck to which my invention is applied, the lifting element is preferably in the form of a lifting link. It is a function of this lifting link to maintain the elevating frame in a lifted position until the lifting link is itself released, whereupon the lifting link moves with the elevating frame into its lowered position. Since the lifting link itself lifts the elevating frame through a spring, hereafter called a lifting spring, it will be appreciated that it will therefore hold the elevating frame in any lifted position through the same spring. Because of this relationship of the parts, when the load is transported with the elevating frame in a lifted position, shocks received by the main frame will be absorbed by the lifting spring interposed between the lifting mechanism and the elevating frame. It is obvious that this contributes easy riding to the load on the elevating frame, which is an extremely desirable condition in many industries in which trucks of the particular class are used.

For controlling the lowering of the elevating frame, there is utilized a dashpot which is secured at one end to the main frame, and at its other end relatively to the elevating frame. It is a feature of my invention that the end of the dashpot which is secured to the elevating frame is secured through the medium of a spring, preferably the lifting spring used in lifting the ele-

vating frame, so that when the load is transferred from the lifting link of the lifting mechanism to the dashpot, the load will be supported by the dashpot through the medium of the spring.

5 It will be appreciated that the shocks incidental to lowering will therefore be cushioned by the spring, and that such action is extremely desirable. It is a further feature of the invention that the spring absorbs whatever play or looseness develops in the several parts, all as will be set forth presently.

As a more detailed feature of my invention, I utilize means to control the lifting and lowering of the elevating frame and the action of the lifting spring, these means being in the preferred form what I term a control cam. Preferably, the control cam is connected to the lifting link for actuation thereby to elevate the frame, and is preferably movable as by rotation relatively to 15 the elevating frame to compress the lifting spring, after which it moves bodily with the elevating frame as the lifting link is operated by the lifting means. It is, of course, through the lifting link and the control cam and lifting spring, that the elevating frame is held in a lifted position.

20 The control cam is preferably connected to the dashpot through what I term struts, whereby to extend the dashpot on lifting movement of the elevating frame, and whereby the dashpot controls the lowering movement of the elevating frame. It is a function of the spring and control cam to take up all play in the dashpot, and in the various linkages at the time that the lifting link is relieved of the load and the load is transferred to the dashpot for control thereby. The 25 spring action is so swift that it absorbs all play in the linkage and dashpot before the load itself may be applied to the dashpot. In this way, there is no shock to the load on the elevating frame as 30 the weight of the elevating frame is transferred from the lifting link to the dashpot.

In testing a truck of the class described, oil was actually removed from the dashpot so that 35 there was play in the dashpot amounting to approximately five-eighths of an inch. This play was taken up by the spring action immediately upon the release of the lifting link for lowering movement, so that the dashpot accepted the load and there was no shock thereto. The extreme 40 value of this construction will, of course, be fully appreciated by those skilled in the art who will understand the significance of the problem which has been met and solved.

One preferred form of the means which I have 45 devised, is shown in the accompanying drawings,

and will be described in this specification, but it should be understood that I consider my invention to be a relatively broad one, and that I expect to obtain claims which will prevent the utilization of my contribution to the art in physical forms other than that herein shown and described. Also, while in describing one form of my invention I shall particularly point out what I now believe is the theory of operation thereof, I do not intend my invention to be limited in scope by that theory.

Referring now more particularly to the drawings wherein is shown a preferred form of my invention, Fig. 1 is a plan view looking down on the truck in which my invention is embodied. Fig. 2 is a side view of the truck of Fig. 1. Fig. 3 is a section taken along lines 3-3 of Fig. 1. Fig. 4 is a view similar to Fig. 3, but showing certain of the parts in different operating positions. Fig. 5 is a view taken along lines 5-5 of Fig. 2. Fig. 6 is a perspective view of the parts of Fig. 5. Fig. 7 is a view looking downwardly on the saddle of the elevating frame showing it in its position of Fig. 3. Fig. 8 is a view looking downwardly on the control cam assembly in its position of Fig. 3.

Referring now more particularly to the drawings, the truck to which my invention is shown applied is, as I have already indicated, shown and described fully in the Stuebing Patent No. 1,785,368. It will, of course, be appreciated that the invention may be applied to other types of trucks, if so desired. Referring now more particularly to Figs. 1 and 2, the truck embodies a main frame 10 formed of side bars 11 and 12, and supported at its rear end by wheels 13 mounted on an axle 14. At the forward end of the truck, the side bars 10 support through suitable means, what is termed in the art a lifting head 15, to which is pivoted a lifting lever 16. The lifting lever 16 operates the lifting mechanism of the truck when swung vertically, and is also adapted to steer the front wheels 17.

For the purpose of this invention, it is merely necessary to consider that when the lifting handle 16 is swung vertically, it actuates the lifting mechanism shown in dotted lines in Fig. 2 and including a pawl 18. The pawl 18 is moved on a pivotal mounting for rotating the lifting ratchet 19 formed integrally with a pair of lifting crank arms 20, there being one crank arm extending outwardly of the lifting head 15 at each side thereof. The crank arms 20 are held in any lifted position by a holding pawl 21 controlled by a foot treadle 22. A depression of the foot treadle 22 effects the movement of the holding pawl 21 out of engagement with the lifting ratchet 19 to allow a lowering movement of the crank arms 20. It is thought that this description of the lifting head and its operation is all that is necessary for an appreciation of the invention, since for a further detailed disclosure, reference may be had to the Stuebing patent.

The elevating frame is designated generally by reference numeral 23, and comprises side bars 24 and 25 connected at their rear by a cross member 26, and at the front end by what is termed in the art a saddle 27. The elevating frame 23 is pivoted to the main frame through a rear link assembly 28, and through forward links 29, all as is well known in this art. Referring now more particularly to Figs. 3-8, inclusive, and especially to Fig. 7, there are secured to the saddle 27 of the elevating frame 23, as by welding, a pair of outer brackets 30 and a pair of inner brackets 31. A front link shaft 32 traverses bores 30a in the

brackets 30 and bores 31a in the brackets 31. The front links 29 through which the elevating frame is mounted for lifting movement relatively to the main frame, are pivoted at their upper ends to the elevating frame through the said link shaft 32.

Mounted also on the shaft 32 and between the inner brackets 31, is what I term a control cam assembly, designated generally by the reference numeral 33 and shown best in Fig. 8. This control cam assembly 33 includes what I term a pair of control cams 34 assembled as by welding to the ends of a tube 35. It further includes a pair of ears 36 spaced from the control cams 34 and also secured as by welding to the tube 35. The control cams 34 are bored as at 34a for pivotal mounting on the link shaft 32, as is clearly illustrated in Figs. 3-6, inclusive. The extreme lower ends of the control cams 34 are bored as at 37 for the passage of pivot pins 38, and through means of the pivot pins 38, each of the control cams is pivotally secured to what I term a lifting link 39. Each lifting link 39 is bifurcated as at 40 whereby to be secured through a pin 41 to one of the crank arms 20. It will therefore be appreciated that a clockwise movement of the crank arms 20 incidental to the lifting operation of the lifting mechanism within the lifting head 15, will effect a counterclockwise rotation of the control cam assembly 33 about the link shaft 32.

For resisting this rotation of the control cam assembly, I utilize a pair of springs 42, each of which is housed within a tube 43 pivoted at 44 to the elevating frame 23. Mounted within each of the tubes 43 and traversing the center of the spring therein, is a rod 45 having a spring compressing disk 46 acting against the extreme left hand end of the spring 42. The other end of each rod 45 is adjustably secured to what I term a spring link 47, which is bifurcated at 48 whereby to be secured to a control cam 34 through the pin 38.

It is obvious that if the crank arms 20 are now rotated in a clockwise lifting direction, the control cam assembly will be rotated in a counterclockwise direction a degree depending on the load which is to be lifted by the elevating frame. Thus, with little or no load, the springs 42 will prevent any rotation whatsoever of the control cam assembly 33 on link shaft 32, so that the control cam assembly will move as a part of the elevating frame 23 through lifting movement of the lifting links 39. When a comparatively heavy load is placed on the elevating frame, it is obvious that the springs 42 must be compressed a degree sufficient to compensate for the weight of the load, and that during this compression, the control cam assembly is rotated somewhat on shaft 32. Thereafter, the springs 42 remain compressed and the control cam assembly moves bodily with the elevating frame as the crank arms 20 and the lifting links 39 move in a lifting direction to move the elevating frame from its position of Fig. 2 to its position in Fig. 3. It is obvious that the load is, in effect, raised through the intermediary of the springs 42, which may therefore be called lifting springs.

Moreover, since the elevating frame is maintained in a lifted position through the use of the holding pawl 21 illustrated in Fig. 2, it is obvious that the elevating frame is held in all lifted positions through the intermediary of the springs 42. Therefore, if the truck is transported over a relatively rough terrain, shock will be transmitted to the lifting frame only through the springs 42,

rather than directly, as is the case in a standard truck. In Fig. 4, I illustrate just what happens when extra shock is transmitted to the load. It will be noticed that the elevating frame will then move from its dash and dot position towards its full line position, and that the springs 42 will be compressed to a considerable degree.

It should be noted that each of the control cams has a surface 50 which is adapted to impinge against a surface 50s of the saddle 27, should the springs 42 fail to function, as through breakage, or weakening, or in any other manner. Thus, should the springs 42 fail for any reason, the cam assembly 33 will rotate until the surfaces 50 contact the surface 50s. Thereafter, the control cam assembly and the elevating frame will be actuated as a single unit by the lifting links 39 in a lifting direction.

Referring now once again to Figs. 7 and 8, taken in conjunction with Figs. 3-6, the control cams 34 have bores 51 in alignment with bores 52 formed in the ears 36 of the control cam assembly 33. As is best illustrated in Fig. 5, pivot shafts 53 extend through the bores 51 and 52 and through bores formed in the lower ends of vertical struts 54. Each of the struts 54 is pivoted through a pin 55 to a further vertical strut 56 and to a guide lever 57. There are, thus, two guide levers 57, each of which is pivoted at 59 to the lifting head 15, it being the function of guide levers 57 to guide the struts 54, 56 in a particular path, all as will be quite clearly indicated hereinafter.

The upper ends of the struts 56 are secured to a tube 61, to which in turn is secured a block 62. This block 62 forms the end of a plunger 63 of a hydraulic check or dashpot assembly 64. The lower end of this dashpot assembly is pivoted through a shaft 65 to plates 66 which are welded as at 67 to the lifting head of the truck. In effect, therefore, the dashpot extends between the main frame and the elevating frame, through the intermediary of the control cam assembly 33, and therefore, through the intermediary of the springs 42. It is obvious therefore, that when the load is transferred to the dashpot through the release of the crank arms 20 by the pawl 21, the lowering of the load will be controlled by the dashpot through the struts 54, 56, the control cam assembly 33, and the springs 42. Functionally, therefore, the lowering is through the intermediary of the springs 42.

Moreover, it will be readily appreciated that with the load on the elevating frame lifted as in the position of Figs. 3 and 4, should the holding pawl 21 be released, the springs 42 will act immediately to move the rods 45 toward the left in Figs. 3 and 4. This will move the spring links 47 toward the left, and will cause an immediate rotation of the control cam assembly 33 sufficient to absorb any play between the spring links 47 and the control cams 34, and between the control cam assembly and the struts 54, 56, and such play as may have developed within the dashpot 64 itself. Thus, for example, should there be a leakage in the dashpot assembly so that there is no oil opposing the drop of the plunger 63 for some distance, the compressed springs 42 will expand and rapidly pick up that distance, thereby preventing the transmission of the shock to the elevating frame and the load thereon. As I indicated earlier in the specification, I have actually tested a truck embodying the construction herein set forth, in which there was a clear space of five-eighths of an inch below the plunger of the dash-

pot. This space was taken up by the action of the springs 42, so that no shock was transmitted to the elevating frame and the load.

While I believe that I have fully described my invention, it may be helpful to review one complete lifting and lowering operation in order to more fully emphasize the coaction of the various parts.

A downward vertical swinging movement of the lifting handle 16 will effect a lifting rotation of the crank arms 20 and the lifting links 39, whereby to rotate the control cam assembly of Fig. 8 a distance necessary to compress the springs 42 sufficiently to compensate for the load on the elevating frame. Thereafter, the control cam assembly will be moved bodily with the elevating frame by the links 39 to elevate the load from the position of Fig. 2 to the position of Fig. 3. Should shock be transmitted to the elevating frame, the elevating frame will move from the dot and dash position of Fig. 4 to its full line position, momentarily more fully compressing the springs 42.

As the elevating platform is lifted, the control cam assembly 33 acts through the struts 54 and 56 to move the plunger 63 of the dashpot assembly from the position of Figs. 2 and 5 to the position of Fig. 3, where the dashpot is ready to check the lowering movement of the elevating frame. If the treadle 22 be now depressed to move the holding pawl 21 out of holding relation to ratchet 20, the crank arms 20 will move from the position of Fig. 3 towards the position of Fig. 2 allowing a lowering movement of the elevating frame.

Should there be any play in the linkage mechanism or leakage of fluid in the dashpot, upon release of the crank arms 20 the springs 42 will operate immediately to absorb that play and to move the plunger 63 down into the dashpot until the liquid therein is encountered. This prevents a transmission of shock which would take place were the elevating frame allowed to drop the distance required to absorb the play in the linkage and in the dashpot. This play is, of course, taken up through the rotation of the control cam assembly 33 relatively to the elevating frame under the influence of the springs 42. Thereafter, there is a gradual lowering of the elevating frame under the control of the dashpot, as is standard in this art.

I now claim:

1. In a truck of the class described, a main frame, an elevating frame mounted for upward lifting movement relatively to said main frame, lifting mechanism on said main frame comprising a lifting link, a spring through the intermediary of which said link is connected to said elevating frame to lift said elevating frame through the intermediary of said spring, a control member movably mounted on said elevating frame and connected to said link for guiding said link as it moves to lift the elevating frame, a dashpot, and means connecting said dashpot to said control member for controlling the lowering movement of said elevating frame.

2. In a truck of the class described, a main frame, an elevating frame mounted for upward lifting movement relatively to said main frame, lifting mechanism on said main frame comprising a lifting link, a spring between said link and the elevating frame through which said link lifts said frame, holding means for holding the lifting mechanism in a lifted position, and whereby said elevating frame is held in lifted position through

the intermediate and
hydraulic dashboard
main frame section
said means that an
so strut and
shock absorber
said con-

take up any play in the dashpot and in its connections to said frames.

10. In a truck of the class described, a main frame, an elevating frame mounted for lifting movement relatively thereto, lifting means for lifting said elevating frame, a dashpot secured at one end to said main frame, a control cam movable relatively to said elevating frame, a spring for resisting said movement of said control cam relatively to said elevating frame, and means securing the other end of said dashpot to said control cam, whereby the said spring is under compression when said elevating frame is supported by said dashpot through said means and control cam.

11. In a truck of the class described, a main frame, an elevating frame mounted for lifting movement relatively thereto, a dashpot secured at one end to said main frame, a control cam pivoted on said elevating frame, a spring for resisting pivotal movement of said control cam relatively to said elevating frame, a strut securing the other end of said dashpot to said control cam, whereby the said spring is under compression when said elevating frame is supported by said dashpot through said strut and control cam, lifting means on said main frame for lifting said elevating frame, and means of connection between said lifting means and said control cam for lifting said elevating frame by first rotating the control cam to place the spring under compression and then moving said control cam and elevating frame together.

12. In a truck of the class described, a main frame, an elevating frame mounted for upward lifting movement relatively to said main frame, lifting mechanism on said main frame comprising a lifting element, a control cam pivoted on said elevating frame and pivotally connected to said lifting element, a spring for resisting rotation of said control cam relatively to said elevating frame, whereby movement of said lifting element actuates said control cam to compress said spring as said control cam rotates relatively to said elevating frame, and to lift the elevating frame when said spring resists further pivotal movement of said control cam relatively to said elevating frame.

13. In a truck of the class described, a main frame, an elevating frame mounted for upward lifting movement relatively to said main frame, lifting mechanism on said main frame comprising a lifting element, a control cam pivoted on said elevating frame and pivotally connected to said lifting element, a spring for resisting rotation of said control cam relatively to said elevating frame, whereby movement of said lifting element actuates said control cam to compress said spring as said control cam rotates relatively to said elevating frame, and to lift the elevating frame when said spring resists further pivotal movement of said control cam relatively to said elevating frame, and means for holding said lifting element in predetermined positions corresponding to certain lifted positions of said elevating frame.

14. In a truck of the class described, a main frame, an elevating frame mounted for upward lifting movement relatively to said main frame, lifting mechanism on said main frame comprising a lifting link, a control cam pivoted on said elevating frame and pivotally connected to said lifting link, a spring for resisting rotation of said control cam relatively to said elevating frame, whereby movement of said lifting link actuates said control cam to compress said spring as said

control cam rotates relatively to said elevating frame, and to lift the elevating frame when said spring resists further pivotal movement of said control cam relatively to said elevating frame, 5 means for holding said lifting link in predetermined positions corresponding to certain lifted positions of said elevating frame, a hydraulic dashpot secured at one end to said main frame, a strut connecting the other end of said dashpot to said control cam whereby said control cam in its rotation relatively to said elevating frame and in its movement with said elevating frame, extends said dashpot when said control cam is actuated to lift the elevating frame, and through said dashpot controls the lowering of the elevating frame.

15. In a truck of the class described, a main frame, an elevating frame mounted for upward lifting movement relatively to said main frame, 20 lifting mechanism on said main frame comprising a lifting link, a control cam pivoted on said elevating frame and pivotally connected to said lifting link, a spring for resisting rotation of said control cam relatively to said elevating frame, whereby movement of said lifting link actuates said control cam to compress said spring as said control cam rotates relatively to said elevating frame, and to lift the elevating frame when said spring resists further pivotal movement 25 of said control cam relatively to said elevating frame, means for holding said lifting link in predetermined positions corresponding to certain lifted positions of said elevating frame, a hydraulic dashpot secured at one end to said main frame, a strut connecting the other end of said dashpot to said control cam whereby said control cam in its rotation relatively to said elevating frame and in its movement with said elevating frame, extends said dashpot when said control cam is actuated to lift the elevating frame, and through said dashpot controls the lowering of the elevating frame when said spring resists further pivotal movement 30 of said control cam relatively to said elevating frame, 35 means for holding said lifting link in predetermined positions corresponding to certain lifted positions of said elevating frame, a hydraulic dashpot secured at one end to said main frame, a strut connecting the other end of said dashpot to said control cam whereby said control cam in its rotation relatively to said elevating frame and in its movement with said elevating frame, extends said dashpot when said control cam is actuated to lift the elevating frame, and through said dashpot controls the lowering of the elevating frame, the spring serving to move the control cam to take up any play in the several parts and the dashpot when the weight of the platform is transferred from said holding means to the dashpot by the release of said holding means.

16. In a truck of the class described, a main frame, an elevating frame mounted for lifting movement relatively thereto, a control cam pivoted on said elevating frame, a spring for resisting pivotal movement of said control cam relatively to said elevating frame, lifting means on said main frame for lifting said elevating frame, and means of connection between said lifting means and said control cam for lifting said elevating frame by first rotating the control cam to place the spring under compression and then moving said control cam and elevating frame together.

17. In a truck of the class described, a main frame, an elevating frame, means mounting said elevating frame for upward lifting movement relatively to said main frame, a lifting member pivoted on said elevating frame, a spring stressing link mounted for endwise movement relatively to said lifting member and for pivotal movement therewith, a spring between said link and lifting member through which said spring stressing link actuates said lifting member to lift said elevating platform relatively to said main frame, and lifting means on said main frame for imparting lifting movement to said spring stressing link.

18. In a truck of the class described, a main

frame, an elevating frame, means mounting said elevating frame for upward lifting movement relatively to said main frame, a lifting member pivoted on said elevating frame, a spring stressing link mounted for endwise movement relatively to said lifting member and for pivotal movement therewith, a spring between said link and lifting member through which said spring stressing link actuates said lifting member to lift said elevating platform relatively to said main frame, lifting means on said main frame for imparting lifting movement to said spring stressing link, and guide means for guiding said lifting member and spring stressing link in their pivotal movement relatively to said elevating platform as said link is actuated by said lifting means to lift said elevating platform.

19. In a truck of the class described, a main frame, an elevating frame, means mounting said elevating frame for upward lifting movement relatively to said main frame, a lifting member pivoted on said elevating frame, a spring stressing link mounted for endwise movement relatively to said lifting member and for pivotal movement therewith, a spring between said link and lifting member through which said spring stress-

ing link actuates said lifting member to lift said elevating platform relatively to said main frame, lifting means on said main frame for imparting lifting movement to said spring stressing link, and guide means for guiding said lifting member and spring stressing link in their pivotal movement relatively to said elevating platform as said link is actuated by said lifting means to lift said elevating platform.

20. In a truck of the class described, a main frame, an elevating frame, means mounting said elevating frame for upward lifting movement relatively to said main frame, a lifting member pivoted on said elevating frame, a spring stressing link, means mounting said link for movement relatively to said lifting member and for movement with said lifting member relatively to said elevating frame, a spring between said link and lifting member through which said spring stressing link actuates said lifting member to lift said elevating platform relatively to said main frame, and lifting means on said main frame for imparting lifting movement to said spring stressing link.

GEORGE QUAYLE.
